UNITED STATES PATENT OFFICE.

COLE STICKLE, OF INDIANAPOLIS, INDIANA, ASSIGNOR TO STICKLE STEAM SPECIALTIES COMPANY, OF INDIANAPOLIS, INDIANA, A CORPORATION.

VENTILATING SYSTEM FOR DRYING APPARATUS.

Application filed November 26, 1923. Serial No. 677,046.

To all whom it may concern:

Be it known that I, COLE STICKLE, a citizen of the United States, and a resident of Indianapolis, county of Marion, and State of Indiana, have invented a certain new and useful Ventilating System for Drying Apparatus; and I do hereby declare that the following is a full, clear, and exact description thereof, reference being had to the accompanying drawings, in which like numerals refer to like parts.

The object of this invention is the better ventilation of rooms in which is located a drying machine or any machine from which vapor arises. This object is attained by means for removing all the vapor from the machine and discharging out of the room so that the air in the room away from the machine will be dry and normal at all times.

Heretofore the vapor rising from such a machine condenses on the roof or any structure in the room above the machine, and drops down on the machine and the work passing through the machine. Take, for example, paper making machines, for which this invention was purposely made, the paper is injured by the dirty condensation water that drops down upon it and also the roof is soon ruined and the other parts of the room, because they are constantly saturated with moisture. The object of this invention is to obviate all that trouble and avoid all vapor or moisture in such room excepting what is immediately in the machine and above it in the hood, through which the moisture or vapor is removed.

The full nature of the invention will be understood from the accompanying drawings and the following description and claims.

In the drawings, Figure 1 is a vertical section through a building showing in side elevation a paper making machine equipped with the invention herein, parts being broken away. Fig. 2 is a transverse section through the building and showing the mechanism in end elevation, parts being broken away. Fig. 3 is a section substantially on the line 3-3 of Fig. 1 through one wall and the ventilating hood and associated means.

The building has a basement floor 10, a main floor 11, walls 12 and roof 13. A paper machine is mounted on the main floor 11, it having the usual cylinders 15 mounted in side supports 16 and 17 and side gearing

18 and steam pipes 19. Below the main floor there are steam supply pipes 20 and 21, a heater 22 and a fan 23 for discharging the heated air into the building above the main floor 11, through a pipe 24, as shown in Fig. 2.

Over the paper making machine there is constructed the hood 25 extending for the full length and width of the machine, A-shaped in cross section and having a curtain 26 extending down from its margins so as to embrace the upper part of the paper making machine to some degree substantially as shown. Along each lower lateral edge of the hood inside thereof there extends a box-like conduit 27 with perforated walls. From said horizontal and longitudinally extending conduits 27 at intervals there are conduits or pipes 28 leading upward. In the top of the hood there is a longitudinal draft chamber 30, preferably dropped somewhat below the top of the hood, the walls of which are perforated so that the vapor rising from the cylinders and main body of the machine will pass through the perforations and enter said draft chamber 30. The lateral air conduits 28 also discharge at their upper ends into said longitudinal draft chamber 30. Beside the middle of the hood there is a multi-blade exhaust fan 31 connected with the central part of said draft chamber 30 by a pipe or conduit 32 and there is a chimney or vent pipe 33 leading from the fan up through the roof 13 and discharging into the open air.

The capacity of the fan and associated inlet and outlet pipes 32 and 33 is such as to create some degree of suction or partial vacuum in the draft chamber 30 and the lateral conduits 28 so that all vapor or steam rising from any part of the machine will be carried away by said apparatus.

The air pressure in the hood is substantially uniform and balanced throughout, because the transverse area of the draft chamber increases from its ends towards its middle portion from which the flue pipe 32 leads. This increase in the size of chamber 30 is in proportion to the transverse area of the tubes 28 entering the same from point to point. Thus the chamber 30, at the entrance of the first pair of tubes 28 near the small end of the chamber, has substantially the same transverse area as the two tubes 28. At the entrance of the second pair of tubes 110

28, the transverse area of the chamber 30 is doubled and it increases correspondingly as other tubes 28 enter it until the outlet at the middle of chamber 20 is reached. Also 5 the tubes 28 are of uniform size and are so throughout their length. This is true also of the side conduits 27. The inlets or perforations to the conduits 27 and 30 also bear substantially the same proportion to the 10 transverse areas of the chambers or tubes which they enter. Wherefore, a uniform balanced pressure will be maintained throughout the hood chamber 30 and conduits 27 and 28, but it will be slightly less 15 than atmospheric pressure because of the suction of the flue pipe 32. Hence, the moisture or vapor rising from the rolls over which the wet paper travels will rise into the central part of the hood and be carried 20 off through the perforations in the walls of the draft chamber 30, whereas the vapor from the sides or lateral portions of the machine and what air is drawn in under the sides of the curtain 26 will pass out through 25 the conduits 27 and tubes 28 into the upper part of the draft chamber 30.

Thus, as heretofore stated, the construction is such that the moisture and vapor will be constantly removed and the air in the 30 room away from the machine be in normal condition.

The heat in the building coming from the heater and fan in the lower part thereof is discharged at the top of the building or 35 roof. It is delivered by the fan 23 into the drying machine room above the main floor in a volume to cause a slight air pressure therein. The roof has no ventilation and, therefore, the warm air discharged in the 40 upper part of the drying room will build down therein to the level of the lower part of the curtain 26 of the hood and any surplus will pass out through the hood. This 45 body of heated air in the upper part of the drying room above the lower edge of the wood will prevent any moisture rising from the machine to the roof where it would condense and drop, as is now the case in practically all paper machine rooms. The body 50 of heated air will build down and the circulation or removal of air from the room will occur at and below the line of the draft tubes 27 in the machine hood. This absolutely prevents any moisture from the drying machine escaping into the room and condensing on the roof or walls of the building, which is a very important feature of this 55 invention, and the static pressure in the hood is such that all the moisture and surplus 60 heated air will pass out through the ventilating apparatus.

Thus in a paper machine making 60,000 pounds of paper in 24 hours, the vapor thrown off by drying would be approximately 140,000 65 pounds, which would equal 5,833 pounds per

hour, or 93.3 cubic feet of water. This illustrates the amount of moisture or water that must be removed and the importance of its removal. This water expanded into steam or vapor form equals 161,280 cubic 70 feet volume per hour, or 2,688 cubic feet per minute. Hence, a fan should be of sufficient capacity to remove at least 2,688 cubic feet of vapor per minute in a paper machine of the capacity indicated. 75

The importance and value of this system of ventilation is indicated by the fact that the volume of heated air heretofore used for removing the vapor by absorbing it was about 500 C. F. M. With this system of 80 ventilating, the vapor can be removed with less than 100 C. F. M., which will be just enough to give an air change in the room. That will give the necessary fresh air ventilation. 85

The invention claimed is:

1. Means for removing vapor from a machine employing moisture, including a hood mounted immediately above said machine and which has a plurality of conduits with 90 perforated walls, a flue conduit leading from said hood, and exhaust means in said flue conduit for maintaining a pressure in said hood less than atmospheric pressure, the relative transverse areas of the conduits 95 in said hood and the perforations in the walls of such conduits being such that the air pressure in them will be substantially uniform.

2. Means for removing vapor from a machine employing moisture, including a hood mounted immediately above said machine, a flue conduit leading from said hood, and exhaust means in said flue conduit for maintaining a reduced air pressure in said hood, 100 said hood having a substantially central inlet chamber for the vapor coming from the machine and also lateral inlet conduits leading to said chamber from the margins of the hood and the relative transverse areas 105 of the conduits and chamber of said hood being such that the air pressure therein will be substantially uniform. 110

3. Means for removing vapor from a machine employing moisture, including a hood mounted immediately above said machine, a flue conduit leading from said hood, exhaust means in said flue conduit for maintaining a reduced air pressure in said hood, 115 said hood having in the central part thereof a depending longitudinally-extending draft chamber with perforated walls for the exit of the main portion of the vapor from the machine, a longitudinally-extending chamber along each side of the hood with perforated walls, and conduits leading at intervals from said side chambers to said central draft chamber, substantially as set forth. 125

4. Means for removing vapor from a ma- 130

chine employing moisture, including a hood mounted immediately above said machine, a flue conduit leading from said hood, exhaust means in said flue conduit for maintaining a reduced air pressure in said hood, said hood having in the central part thereof a depending longitudinally-extending draft chamber with perforated walls for the exit of the main portion of the vapor from the machine, a longitudinally-extending chamber along each side of the hood with perforated walls, conduits leading at intervals from said side chambers to said central draft chamber, and a curtain extending down from the margins of said hood so as to envelope the upper portion of the machine.

5. Means for removing vapor from a machine employing moisture, including a hood

mounted immediately above said machine, a flue conduit leading from said hood, exhaust means in said flue conduit for maintaining a reduced air pressure in said hood, said hood having in the central part thereof a depending longitudinally-extending draft 20 chamber with its greatest transverse area at said flue conduit and tapering therefrom to the ends thereof and with perforated walls for the exit of the main portion of the vapor from the machine, a longitudinally-extending chamber along each side of the hood with perforated walls, and conduits leading at intervals from said side chambers to said central draft chamber, 25 substantially as set forth. 30

In witness whereof, I have hereunto affixed my signature.

COLE STICKLE.
